(57) CLAIM

The ornamental design for a fireproof battery organizer storage box, as shown and described.

DESCRIPTION

FIG. 1 is a perspective view of a fireproof battery organizer storage box showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the fireproof battery organizer storage box; and,

FIG. 9 is an enlarged view of the selected portion in FIG. 1. The broken lines shown in the drawings depict portions of the fireproof battery organizer storage box in which the design is embodied that form no part of the claimed design.
